CLAIM

The ornamental design for an automobile lock scratch guard, substantially as shown and described.

DESCRIPTION

FIG. 1 is a front view of an automobile lock scratch guard showing our new design;

FIG. 2 is a right side view thereof, the left side being a mirror image;

FIG. 3 is a rear view thereof;

FIG. 4 is a bottom view thereof;

FIG. 5 is a sectional view taken on line 5—5 of FIG. 1;

FIG. 6 is a front view of a second embodiment of the design of FIG. 1, the rear being flat and unornamented;

FIG. 7 is a right side view of FIG. 6, the left being a mirror image;

FIG. 8 is a bottom view of FIG. 6.
